UNITED STATES PATENT OFFICE.

EDWIN F. HENDERSON, OF WEST ALLIS, WISCONSIN.

THERAPEUTIC TRUSS.

1,133,958.

Specification of Letters Patent. Patented Mar. 30, 1915.

Application filed February 4, 1914. Serial No. 816,604.

To all whom it may concern:

Be it known that I, EDWIN F. HENDERSON, a citizen of the United States, residing at West Allis, in the county of Milwaukee and State of Wisconsin, have invented certain new and useful Improvements in Therapeutic Trusses; and I do hereby declare the following to be a full, clear, and exact description of the invention, such as will enable others skilled in the art to which it appertains to make and use the same.

The primary object of this invention is to provide a therapeutic truss of compact, simple and inexpensive construction, which may be readily applied to the male organ of generation to produce a mechanical erection by damming the outward flow of blood.

Another object of my invention is to provide a device which, because of its scientificness in construction, is productive of strong curative effects, so that after a time the organ becomes revitalized and capable of erection without artificial assistance.

With these and other objects in view as will become more apparent as the description proceeds, the invention consists in certain novel features of construction, combination and arrangement of parts as will be hereinafter more fully described and claimed.

For a complete understanding of my invention, reference is to be had to the following description and accompanying drawings, in which—

Figure 1 is a front elevation of my truss, Fig. 2 is a rear elevation thereof, Fig. 3 is an inside elevation, showing the truss in position, the organ being shown in cross section, Fig. 4 is a transverse sectional view through the device on the plane of line 4—4 of Fig. 2, and Fig. 5 is a similar view, showing the truss extended in the position it assumes when in use.

In order that all the merits of my invention, its scientific construction, and especial adaptability for the object in view, may be fully appreciated, a brief reference to the formation and natural operation of the organ will be made.

Referring to Fig. 3, A designates the superficial dorsal vein and B the deep dorsal vein, which as shown, extend longitudinally along the top of the organ. C indicates the dorsal artery and D the dorsal nerve. E indicates the corpora cavernosa, F the cavernous arteries, G the corpus spongiosum, and

H the urethra. Underneath and at the base of the organ is a muscle called the erector muscle, which when excited automatically contracts and constricts the veins A, B and C, that return the blood or allow it to flow away from the organ to the body. In other words it acts to dam the outflowing stream of blood, causing the erectile tissue of the corpora cavernosa to be distended because of a surcharge of blood. The superficial dorsal vein and the deep dorsal vein carry away the major portion of the blood, and the corpus spongiosum feeds the blood into the organ. My truss mechanically cuts off the return flow of blood by exerting a pressure upon the upper side of the organ to compress the veins located there, which carry the blood away. It operates in a manner closely analogous to the natural and produces no harmful effects.

Referring now to the construction of my truss, 1 designates the body formed of some soft flexible material, such as rubber, and of a substantially elliptical shape when flattened out. The body, when in its normal position appears concavo-convex in cross section, having its inner or rear face 2 concave and its outer face 3 convex. The body is formed on opposite sides of its transverse center with circular openings 4 which are spaced some little distance from each other, and with a slit 5 which severs the portion of the body between the openings, forming tongues 6 and 7. The lower tongue 7 has formed thereon preferably integrally, a rubber cushion 8 which extends transversely of the body and which is in the form of an arched layer of rubber. It will of course, be understood that the exact size, shape and construction of the cushioning element is immaterial so long as it properly performs its function, which will be hereinafter set forth.

The truss is slipped over the organ when in its normal state and worked back toward the abdomen with the concave side 2 facing inwardly. The tongue 6 is turned inwardly and lies with its outer face in contact with the upper side of the organ directly over the blood returning veins A and B and exerts a sufficient pressure to check the outward flow of blood. The erectile tissue within the corpora cavernosa is forced into the apertures or openings 4 and the inner end of the cushion presses against the erector muscle.

From the foregoing description taken in connection with the accompanying drawings, it will be apparent that I have provided a very simple therapeutic truss constructed on scientific lines, which in use causes blood to be forced into the tissue of the corpora cavernosa resulting in an erection. By repeated use of this device, the organ is revitalized and restored to a healthy condition, so that it may perform its natural function without the aid of mechanical devices or drugs.

While I have shown and described the preferred embodiment of my invention, it will be understood that minor changes in construction, combination and arrangement of parts may be made without departing from the spirit and scope of the invention as claimed.

Having thus described my invention, I claim:

1. A therapeutic truss comprising a body of flexible material, said body being concavo-convex in cross section, said body also having a pair of spaced openings formed therein and a slit connecting the openings, said slit dividing the body between the openings into a pair of tongues, and a cushioning element extending transversely of the body along its inner side.

2. A therapeutic truss comprising a body of flexible material, said body being concavo-convex in cross section, said body also

having a pair of spaced openings formed therein and a slit connecting the openings, 35 said slit dividing the body between the openings into a pair of tongues, and a cushioning element extending longitudinally of one of said tongues along its inner side.

3. A therapeutic truss comprising an elongated body of flexible material concavo-convex in cross section, said body being formed along the line of longitudinal center with a pair of spaced circular openings, and a slit connecting said openings, said slit dividing the body between the openings into a pair of tongues, and a cushioning element 45 extending transversely of the body along the inner side.

4. A therapeutic truss comprising an elongated body of flexible material, said body being concavo-convex in cross section, said body having a pair of spaced circular openings formed therein along the line of its longitudinal axis, and a slit connecting the 55 openings, said slit dividing the body between the openings into a pair of tongues, and an integral cushioning element extending transversely of the body along one of the tongues on its inner side.

In testimony whereof I affix my signature in presence of two witnesses.

EDWIN F. HENDERSON.
